NONRUN BARRIER FOR KNITTED STOCKINGS

Albert E. Margerison, Philadelphia, Pa., assignor
to Northwood Hosiery Company, Philadelphia,
Pa.

Application November 28, 1933, Serial No. 700,031

2 Claims. (Cl. 66—172)

This invention relates to a nonrun barrier course for the toe fabric of knitted stockings.

The principal object of the invention is to provide a barrier course for the toe fabric of the stocking during the knitting thereof and so constructed that runs will be prevented from passing in either direction walewise of the fabric.

A feature of the invention is the provision of a barrier composed of knitted loops constructed and interlooped in a unique manner to prevent runs from passing thereby in either direction of travel.

My invention is also distinguished in extending the spread interlocking loops of the companion interlocking courses in opposite directions to balance the fabric and to positively insure non-run characteristics but I wish it to be understood that the spread interlocking loops of both courses may extend in the same direction depending upon what is most desirable in practice.

With these and other objects in view, the invention will be better understood from the following detail description taken in connection with the accompanying drawing, wherein:

Figure 1 is a side elevation of a stocking constructed in accordance with my invention.

Figure 2 is an enlarged view of the toe fabric blank.

Figure 3 is an enlarged view of a portion of the toe fabric.

Again referring to the drawing, it will be noted that in Figures 1 and 2 the nonrun barrier 1 extends entirely across the toe fabric 2 but I wish it to be understood that the barrier may be constructed to only extend part way across the toe fabric depending upon what is most desirable in practice.

In Figure 3 I have illustrated the nonrun barrier as consisting of an interlocking course 3, a plain course 4 and a second interlocking course 5. Each of the interlocking courses 3 and 5 consists entirely of spread interlocking loops 6 each extending from the needle wale in which it originated across into an adjacent needle wale and interlocked with an adjacent spread loop. I also wish to call attention to the fact that the spread interlocking loops of course 3 extend in an opposite direction to those in course 5 but I wish to be understood that all the spread interlocking loops of both interlocking courses may extend in the same direction depending upon which is the best under existing manufacturing conditions. By providing the two interlocking courses at a point in the toe fabric spaced from the end there-

of, I positively prevent runs from passing from the toe fabric into the foot and instep portion of the stocking. This is a great advantage when taking into consideration the degree of sheeress of present types of sheer silk stockings and the fact that quite often holes are formed in the end of the toe fabric in the use thereof.

I am aware of the fact that barrier courses have been used before in the toe fabric and various parts of the stocking but these particular barrier courses are of the well known transferred loop type which will only prevent runs from passing in one direction and will not prevent runs from passing in both directions walewise of the fabric. In other words, my type of barrier accomplishes completely the desired result whereas a transferred loop barrier course will only partially accomplish the desired result and when used in the toe fabric is absolutely impractical in so far as preventing runs from passing from the toe fabric into the sheer instep fabric of the stocking.

Having described my invention, what I claim is:

1. In the toe section of a knitted stocking, a nonrun barrier extending across said toe section and comprising a pair of courses; each course consisting entirely of nonrun interlocking loops; every loop in one of said courses having a portion spread from its own needle wale to the next needle wale in one coursewise direction and interlooped with the loop in said next needle wale; and every loop in the remaining of said courses having a portion spread from its own needle wale to the next needle wale in the other coursewise direction and interlooped with the loop in said last mentioned needle wale.

2. In the toe section of a knitted stocking, a nonrun barrier extending across said toe section and comprising a pair of courses; each course consisting entirely of nonrun interlocking loops; every loop in one of said courses having a portion spread from its own needle wale to the next needle wale in one coursewise direction and interlooped with the loop in said next needle wale; and every loop in the remaining of said courses having a portion spread from its own needle wale to the next needle wale in the other coursewise direction and interlooped with the loop in said last mentioned needle wale; and a course of plain knit loops interposed between said pair of nonrun courses and interlooped with the interlocking spread loops of the latter.

ALBERT E. MARGERISON.
